SLIP LAST

George Clausing, Portsmouth, Ohio, assignor to
 Vulcan Corporation, Portsmouth, Ohio, a corporation of Ohio

Application September 1, 1944, Serial No. 552,238

3 Claims. (Cl. 12—136)

1

This invention relates to shoe lasts and more particularly to the type known as "slip" lasts which are inserted into the shoe after it has been sewed up and the upper has been sewed to the insole of the shoe.

Expandable and contractible lasts have been provided for use in the manufacture of shoes where the upper is substantially completed before the last is inserted. However, many of the lasts of this type, as exemplified by the applicant's Patents Nos. 2,047,309 and 2,065,655, when in extended position, are not solid and depend on the use of slides and other mechanism for their operation. The last of the present invention also differs from the usual hinged lasts which are "flexed" so that they are more readily removable from the finished shoe.

The primary object of the present invention is to provide a "slip" last which is substantially solid and full throughout, in its extended position, and which is of simple construction and easy to operate.

Another object of the invention is to provide a "slip" last which may be very substantially shortened for insertion and removal from a shoe.

A further object of the invention is to provide a "slip" last which can be removed from the finished shoe without marring its shape.

An important feature of the present invention is the provision of a shoe last divided into heel and toe portions by a saw-cut which is at a substantial acute angle to the normal axis of the last, or at a substantial acute angle to the tread of the last. The surfaces formed by the saw-cut provide sliding surfaces for the relative movements of the toe and heel sections so that the last may be shortened by sliding the heel and toe parts toward each other along the saw-cut under control of a guiding and limiting link.

Another important feature of the invention is to provide a slip last which can be materially shortened for insertion into the sewed upper of a shoe, and which is provided with a simple means for locking it in extended lasting position so that the final lasting operations can be carried out. The locking means of the present invention is of simple design and readily operated for releasing the last parts.

According to the preferred form of the invention, the improved slip last comprises a toe part and a heel part slidably movable relative to each other on a forwardly and upwardly extending surface which is at an angle to the tread or bottom of the last. The last includes a connecting link for the toe and heel parts, for holding them to-

gether in alignment and for limiting the relative movement of the heel and toe parts, the link being at an obtuse angle to said surface when the heel part is in its normal extended position.

According to the present invention, the sliding surface or surfaces between the heel and toe parts of the last may be curved or straight, and other changes made within the scope of the invention. Other objects, features and advantages of the invention will also appear from the following more detailed description thereof, taken in connection with the accompanying drawing, in which:

Fig. 1 is a side elevational view of a last constructed in accordance with the present invention, with parts broken away to show the link in elevation and the locking means in section. The full line drawing shows the last in extended position while the dotted heel portion shows the last in shortened or contracted position.

Fig. 2 is a view similar to that of Fig. 1, showing a modified form of last.

Figs. 3, 4 and 5 are broken side elevational views of further modified forms of the improved slip last of the present invention in which the full line drawing shows the last in its extended position while the dotted lines show the contracted arrangement.

Fig. 6 is a broken view showing a modification of the last of Fig. 5.

The preferred form of the invention is illustrated in Fig. 1 of the drawing which shows a shoe last comprising a toe part 18 and a heel part 12 connected together by a relatively heavy flat metal link 14 anchored to the toe and heel parts by pins 16 and 18. The toe and heel parts 18 and 12 are separated by a stepped transverse cut line 19 which extends upwardly and forwardly from the forward portion of the heel seat through the upper portion of the instep of the last. This cut may be at any suitable angle with respect to the tread or axis of the last. The cut provides oppositely disposed flat engaging surfaces which match each other exactly and shoulders 21 which engage each other when the last is in extended position, as shown in the full line view. In contracted position the toe and heel parts are moved relative to each other with the cut line surfaces substantially in alignment to the dotted line position which very substantially shortens the last and permits its insertion into a sewed upper of a shoe. This shortening also permits its ready removal from a lasted shoe without marring its shape.

The link 14 is a heavy flat piece of metal which is mounted in respective vertical slots of the toe and heel portions of the last, the slots being cut to the thickness of the link so that the toe and heel parts of the last are kept in proper alignment. The pins 16 and 18 are located so that a line through them extends at approximately the obtuse angle shown with respect to the angle of the cut 19 between the toe and heel portions of the last. This angle which is a substantial obtuse angle permits the movement of the link to the dotted line position and a substantial reduction in the length of the last. The link limits the extension of the last so that the cut surfaces exactly match each other and a solid full last is provided for the lasting and forming of the shoe.

The heel part 12 of the last is locked with respect to the toe part when the last is in its extended position by means of a locking mechanism which operates between the surfaces of the cut 19 above the link 14. The locking means comprises a cylindrical member 20 mounted in the toe part which carries a plunger 22. The cylindrical member 20 is tightly fitted in a hole while the plunger 22 is forced outward from the cut surfaces of the toe part by means of a spring, as shown. The plunger 22 extends substantially into a cylindrical member 24 in the heel part to lock the parts of the last in their normal extended position. The plunger 22 is disposed so as to be released from the heel part by means of a plunger 26 mounted in the heel part and extending into the cylindrical member 24. The plunger 26 is keyed to the heel part of the last by means of a pin set through a recess 28 in the side of the plunger 26. The heel portion of the last is released by depressing the plunger 26 and forcing the plunger 22 into the toe part 10 so that the cut surface of the heel part is slideable along the cut surface of the toe part to the dotted line position. The pin in the recess 28 and the shoulder construction of the plunger 26 prevents its entry into the cylindrical member 20. When the heel part 12 is moved into extended position the spring-operated plunger 22 snaps the plunger 26 to its outward position.

In making a last such as described in connection with Fig. 1 of the drawing, the solid last may be turned to the desired shape, from a block of maple or any other suitable material and toe and heel finished. The holes for the pins 16 and 18 are then drilled and the last sawed in two along the line 19 as indicated, to provide separate toe and heel positions. The slots for the link are then cut in the toe and heel portions, preferably to one side of the center, so that they do not interfere with the hole for the locking mechanism. The last is then assembled by anchoring the link in the slots by means of the anchor pins 16 and 18. It is then drilled centrally from the upper portion of the last to make the hole for receiving the locking mechanism and that for the metal liner 30, which is provided for receiving a jack pin. The liner 30 is then pressed into place and the various parts of the locking mechanism are mounted in the toe and heel portions.

The modified form of the slip last shown in Fig. 2 includes the same link and lock construction as that of the last shown in Fig. 1, and differs only in the shape of the cut separating the toe and heel portions 10 and 12. In Fig. 2, the cut 32 is a transverse cut having a step or shouldered stop 33 as in Fig. 1, which begins at about the same position with respect to the heel seat as in Fig. 1, but it extends upwardly and forwardly in a curved

line which terminates at or near the top of the instep of the last. In this form of the invention a substantially greater amount of the instep of the last is retained on the toe portion than in Fig. 1. In operation, the last of Fig. 2 is similar to that of Fig. 1, but when the heel portion is released and moved forward, it follows the curve of the cut line to the dotted line position as indicated. In making a shoe, the toe portion 10 is inserted in the sewed upper with the heel portion 12 in the dotted line position, and then the heel portion is slid down the slope of the cut 32 into the heel of the shoe, the heel portion 12 therefore follows the arc of the cut line 32 into the bottom of the shoe, and forces the shoe into the desired shape.

The modified form of the slip last shown in Fig. 3 comprises a toe portion 34 which includes all of the instep portion of the last and a heel portion 36 attached by a link 14 and anchor pins 16 and 18. The toe and heel parts of the last in this instance does not include the entire volume of the original last, but a certain portion is cut away to provide for the relative movement of the heel and toe sections. The toe section has a transverse surface 38 extending downward from the top of the instep, a curved surface 40, a shoulder 42, and a lower curved surface 44, all transverse to the last. The heel part of the last includes an upper transverse surface 46, a curved surface engaging the surface 40, and a curved surface engaging the surface 44. The heel section also has a shoulder surface 48 engaging the shoulder surface 42 of the toe section when the last is in extended position. The cut out portion in the upper portion of the last leaves a transverse space between the surfaces 38, 40 and 46. When the last is shifted to contracted position, the surface 46 is moved up toward the surface 38 as indicated by the dotted line position of the heel part, while the curved surfaces of the heel part slide along the surfaces 40 and 44.

When the last of Fig. 3 is in extended position, the shoulder 48 is in engagement with the shoulder 42 and the toe and heel parts of the last are held in this position by means of a round-headed snap catch 50, mounted in the surface 44 of the toe part. The round head of the catch 50 projects into a ferrule 52 mounted in the surface of the heel part, so that the heel and toe parts of the last are held in extended position unless sufficient force is applied to overcome the spring in the snap catch 50. Instead of having the surfaces 40, 44, and the corresponding surfaces on the heel part, curved as shown, they may be straight, as in Fig. 1, and the intervening shoulder also be present, or the surfaces may be curved in the reverse direction, as in Fig. 2, and the shoulder included.

A further modification of the slip last as shown in Fig. 4 includes three parts, a toe part 54, a central part 56, and a heel part 58. In the normal position of the last, these parts fit together to form a complete last without any cut out portions, as clearly indicated by the full line view. The central section has the general shape of a keystone, and when it is moved up to the dotted line position, the heel part moves in toward the toe part to very substantially reduce the length of the last, as shown by its dotted line position. The keystone section 56 is anchored to the toe part by means of a link 60 and anchor pins 62 and 64. It is also anchored to the heel part by a link 66 and anchor pins 68 and 70. When the last of Fig. 4 is in extended position, the keystone section 56 completely intervenes between

the toe and heel parts 54 and 58 and is provided with front and rear shoulders which engage correspondingly stop shoulders of the toe and heel parts of the last so that the parts are exactly positioned vertically. In this position the pins 64 and 68 are below the line between the pins 62 and 70, so that when the last is in a shoe, the keystone section will be firmly held between the toe and heel parts of the last. This will be apparent from the fact that in order to have the pins 64 and 68 move above the line of the pins 62 and 70, there would have to be some additional separation between the toe and heel parts 54 and 58. The tension of the shoe upper holds the last parts in normal position.

The links 60 and 66 are preferably relatively heavy flat pieces of metal similar to links 14, and are set in vertical slots which maintain the alignment of the respective parts of the last. When it is desired to insert or remove the last from a shoe upper, the keystone section 56 is simply pulled up (by any suitable means) to the dotted line position shown in Fig. 4, thereby shortening the last. The last of Fig. 4 is similar in function to the last of Fig. 1, because it is provided with a transverse cut line between parts 54 and 56 which extends at an acute angle to the longitudinal axis of the last. The use of the keystone section 56 which moves upwardly, however, permits a substantially horizontal movement of the heel part 58, so that it may be pushed directly back into the heel of the sewed shoe upper which is to be stretched to shape. The line or cut between parts 56 and 58 is also at an acute angle to the axis of the last and therefore contributes to the shortening of the last. Means other than the steps or engaging shoulders may be used for correctly positioning the parts of the last.

Fig. 5 shows a slip last which is a modification of the last shown in Fig. 1 and comprises a toe part 72 and a heel part 74 separated by a transverse broken saw-cut line 76. The upper and lower straight portions of the saw-cut line 76 run in the same direction and are connected by a step comprising a shoulder on the heel part 74 and a shoulder on the toe part 72 which engage each other and determine the proper position of the toe and heel parts of the last when the last is in extended position. It will be noted that the saw-cut line 76 runs at an acute angle to the axis of the last but in the opposite direction to that of the line 19 in Fig. 1. A locking means comprising a flat plate or bar 78 is pivoted to the top of the heel part 74 and when in locking position one end overlies a portion of the toe part adjacent the line 76. When the flat bar or plate 78 is turned crosswise of the last, the toe and heel parts may be moved relative to each other, that is, the heel part may be pushed down with respect to the toe part, or the toe part may be pulled up with respect to the heel part, and thereby shorten the last for insertion into or removal from the upper of a shoe.

In Fig. 5, the saw-cut line 76 extends through the portion of the heel normally mounting the thimble for the jack pin, and therefore this element of the last is shown as set in the toe part 72.

Fig. 6 shows a modification of the last of Fig. 5 in which the saw-cut is curved. In this figure, the saw-cut is opposite to that in Fig. 2, and it will be noted that the toe and heel parts 72 and 74 are pivoted together by the same means, as in Figs. 1, 2 and 5, and that a broken curved transverse saw-cut line 80 extends from the upper por-

tion of the heel part 74, downwardly and forwardly to and through the instep of the last. The saw-cut line 80 is broken to provide a step having engaging shoulders for the parts 72 and 74 which determine the position of the parts of the last in its extended position, and which provide means by which the toe and heel parts are caused to match each other exactly. The locking means may be the same as in Fig. 5.

Instead of having a single curved saw-cut line 80, as in Fig. 6, the improved last may include two curved shouldered cuts, extending in substantially opposite directions, somewhat like the saw-cuts in Fig. 4, so that an intermediate part of the last is provided. Such an intermediate section may be pivoted by links to the toe and heel sections as in Fig. 4, and functions in the same manner as the keystone-shaped part 56.

It is to be understood that in all the forms of the slip last, as shown and described, the saw-cut lines may be unbroken and other stop means used for insuring the proper matching of the respective parts of the last in its full or extended position. In certain instances, such as for example in Figs. 1 and 2, the locking means in connection with the link 14 would be sufficient to insure the matching of the toe and heel parts of the last if the saw-cut 19 were a straight cut or the curved saw-cut 32 were a continuous curve.

A slip last made in accordance with the features of the present invention in any of the various modifications may be used for the manufacture of shoes in the conventional way, but the slip last is particularly useful and preferably used where the upper is previously sewed to the inner sole, or sock-lining, and then pulled over the last and the last extended. The outer sole as well as the heel may be attached to the shoe upper while it is still on the last, after which the last may be readily shortened by putting it on a jack post, unlatching or unlocking the two sections, collapsing the last to substantially shorten it, and then pull the last out of the shoe.

It will be apparent from the foregoing description that the slip last of the present invention may be used in various ways, and may be modified in certain respects. Other modified forms may be made. These changes are contemplated as coming within the spirit and scope of the present invention, as defined by the claims.

Having described the invention in its preferred form, what is claimed as new is:

1. A collapsible slip last adapted to be inserted into a sewed shoe upper and used in the forming and lasting of the shoe, comprising in combination a toe part and a heel part separated from each other by an intermediate keystone-shaped part having matching engaging surfaces respectively with the toe and heel parts of the last, said surfaces being substantially transverse to the last and at an acute angle to the longitudinal axis of the last, a link connecting the toe part to said intermediate keystone-shaped part, a link connecting the heel part with said keystone-shaped part, the ends of the links connected to the keystone-shaped part being below a line through the opposite ends of the links when the surfaces of the parts are in their normal engaging position.

2. A collapsible slip last as defined by claim 1 in which said matching engaging surfaces include a shouldered step for exactly positioning the toe and heel parts with respect to the keystone-shaped part.

3. A shoe last, comprising in combination a toe part and a heel part separated from each other by an intermediate upright keystone-shaped part having shouldered surfaces respectively matching and engaging corresponding surfaces on the toe and heel parts of the last, said surfaces being generally transverse to the last and at an acute angle to the longitudinal axis of the last, a link connecting the toe part to

said intermediate keystone-shaped part, a link connecting the heel part to said keystone-shaped part, the ends of the links connected to the keystone-shaped part being below a line through the opposite ends of the links when the surfaces of the parts are in their normal engaging position, whereby the parts of the last are locked in extended position by end compression of the last.

GEORGE CLAUSING.
